UNITED STATES PATENT OFFICE.

WILLIAM F. LAUTENSCHLAGER, OF CINCINNATI, OHIO, ASSIGNOR TO THE PEERLESS MACHINERY COMPANY, OF BOSTON, MASSACHUSETTS, A CORPORATION OF MASSACHUSETTS.

GAUGE FOR PERFORATING MACHINES.

Application filed January 17, 1924. Serial No. 686,816.

This invention relates to a gauge for perforating machines and more especially to one adapted for positioning small parts of irregular contour.

5 In the shoe manufacturing industry at the present time, many styles of shoes, especially women's shoes, call for the perforating of various parts, many of which are comparatively small and of irregular contour, with 10 more or less varied and complicated cut-out and perforated designs. Heretofore, owing to the difficulty of gauging such parts accurately in the perforating machine, it has been customary to cut the part from the 15 stock somewhat larger than the finished product and to provide the die for perforating the desired pattern with a cutting edge surrounding the pattern to cut the part the required form and size. The die thus cuts 20 out the part and perforates the pattern in it simultaneously, thereby securing the accurate positioning of the perforating on the part. This method is, however, wasteful of 25 the stock and requires the addition to the die of a knife edge for cutting out the part, both of which considerations add greatly to the expense of these parts. When the parts have a beaded edge, however, which work must be done before the perforating operation, then an extra die minus the outline 30 knife edge is necessitated and the gauging of such parts in proper position in the machine requires care and time slowing down appreciably the speed of the operation.

35 The main object of my invention is the provision of a gauge for perforating machines whereby shoe parts may be rapidly and accurately positioned in the machine, thereby speeding up the work and obviating 40 all danger of the perforated design being twisted or out of position or alignment in the part.

Another object of the invention is to simplify and reduce the cost of the dies used 45 for this work by rendering the outline cutting knife unnecessary and thereby to perforate both beaded and raw edge parts with the same die.

50 Other objects of the invention will be more specifically set forth and described herein-after.

In one of its forms my invention contemplates the provision of a gauge, preferably in plate form, provided with a cut-out por-

tion, recess or opening, suitably shaped to 55 receive and hold the shoe part to be perforated by frictional contact with its entire edge, the gauge being provided with suitable means whereby it may be expeditiously mounted in absolutely accurate position in 60 the machine for the perforating operation. By providing a number of these gauges and by having them filled with shoe parts to be 65 perforated by unskilled labor, it is possible for the skilled operator of the perforating machine to insert and remove loaded gauges and operate the machine with great rapidity.

If desired, the shoe part holding recess may be provided with a suitable inwardly 70 projecting flange on the reverse side of the gauge to afford a better support for the edge of the shoe part and the frictional engagement, or on the reverse side of the gauge, the entire recess may be covered over by 75 perforatable material for supporting the shoe part. The mere fact that this support will be perforated with the design on the first use of the gauge, will not in any material degree affect its use afterwards as a supporting means.

80 In the drawings illustrating one form of my invention, Figure 1 is a plan view of the work support of the machine illustrated in United States Letters Patent No. 1,434,060, issued to me October 31, 1922, having one 85 form of my invention applied thereto; Fig. 2 is a central cross-sectional view on line 2—2 in Fig. 1; Fig. 3 is a view in perspective of a small portion of the gauge adjacent the cut-out or recessed portion drawn on an enlarged scale to illustrate the character of the 90 edge of the opening or recess which is adapted to hold the shoe part therein by frictional contact; Fig. 4 is a detailed sectional view of the means provided for accurately positioning the gauge in the machine for the 95 perforating operation; Fig. 5 is a plan view of the gauge looking towards its right side and showing the cut-out portion or shoe part holding recess provided with an inwardly 100 extending flange on the reverse side of the gauge for supporting the edge of the shoe part; Fig. 6 is a cross sectional view on line 6—6 in Fig. 5; Fig. 7 is a view similar to Fig. 5 but showing the shoe part holding recess entirely closed on the reverse side of the gauge with a layer of perforatable material for supporting the shoe part in the re-

cess, and Fig. 8 is a sectional view on line 8—8 in Fig. 7.

In the illustrated embodiment of the invention there is shown a gauge in the form 5 of a plate 10 provided with a cut-out portion, recess or opening 12 of the size and contour of the shoe part to be perforated. The plate may be of any suitable area and size dependent, however, to some extent upon 10 the size of the shoe part and the size and construction of the machine in which it is to be used or it may be made in various sizes. The size, however, is not material so long as it projects a sufficient distance from 15 the machine, when in operative position, to afford the operator free and ample opportunity to grasp its forward end for handling. The plate may be made of any suitable light, strong and easily handled material, such 20 as cardboard, leather-board or similar material and I have found that "pattern board" commonly used in shoe factories for making patterns for cutting out shoe parts is well adapted for this use.

25 The edge 14 of the opening 12 is preferably roughened to increase its frictional holding power upon the edge of a shoe part placed in the opening and this end may be accomplished in any suitable manner such as by forming the recess or opening 12 by 30 the use of a grading machine which cuts a corrugated edge with the corrugations perpendicular to the plane of the plate.

For positioning the plate in the perforating machine various means may be employed and one such is shown comprising a pair of holes 16 spaced apart in the plate 10 adapted to engage with frictional tightness suitable pins 18. The holes 16 may be protected against wear by eyelets clenched therein. The pins 18 may be fixed either on the work-support of the machine if the latter's construction and operation permit or on the frame of the machine or on a separate support 20 as shown in the drawings. The gauge support 20 is substantially U-shaped in general outline and may be mounted on the work-support 22 by means of two pins 24, one in the end of each arm 26, each 40 adapted to fit in a hole 28 in the work-support and to be held therein by a knurled headed screw 30, threaded through the end of the work-support to bear against it. A nut or washer 32 on each pin 24 and a lug 50 34 riveted further forward to each arm 26, both on the under side thereof, serve to hold the support slightly above the top surface of the work support to prevent interference with a buffer or backer strip 36 and to hold 55 the gauge support against tilting motion.

The forward portion of the gauge-support indicated as 20 is slightly offset downwardly in relation to the two arms 26 to bring its upper surface on a level with the 60 top-surface of the buffer-strip 36 so that

the surfaces upon which the plate rests when in operative position may lie in the same plane as shown in Figure 2.

In the top surface of the work-support may be arranged a plate 38, preferably of soft brass, to protect the cutting edges of the die. As a general rule this function is performed by the buffer strip but the provision of the brass plate is an added security.

In Figures 5 to 8, inclusive, is shown a form of gauge in which the shoe part holding opening or recess 12 is provided with additional means for insuring the retention of the shoe-part therein during the handling of the gauge and the perforating operation. In the ordinary run of shoe parts these means may not be necessary since the usual stiffness of those parts will hold them in frictional contact with the edge of the recess 12 to prevent falling out. In other cases, however, where the parts are large and made of very light or flimsy leather, it may be found desirable to provide means in addition to the edge frictional means for holding them in place.

In Figures 5 and 6 the edge of the recess 12 of the gauge is shown as having a flange 40 on its reverse or bottom side extending inwardly toward the center of the recess which further supports the shoe part in position. This flange may be made in any suitable manner but preferably is formed by pasting a strip of thin, hard paper around the edge of the recess on the reverse side of the gauge.

In Figures 7 and 8 is shown a construction in which the recess is entirely closed on the back of the gauge by thin paper 42 pasted thereon. This forms a pocket in the front face of the gauge adapted to receive and hold the shoe part securely therein no matter how thin or flexible it may be. The paper 42 in this latter form will of course be perforated with the design cut on the shoe part the first time the gauge is used but since each gauge will be used for but a single shape and size such perforations will not affect the operation of the back 42.

In the use of my invention, the operator takes a gauge having a recess adapted to receive the shoe parts about to be perforated, places a part in the recess in proper position, lays the gauge on the work-support and presses it down upon the positioning pins and then starts the machine which makes one perforating operation and stops as is usual with machines of this character. In placing the gauge in position the operator handles it by that portion which projects forwardly over the gauge support, retains her hold upon it and instantly removes it from the machine when perforated and then removes the part from the gauge which last act may be accomplished by lightly tapping the rear end of the gauge against a fixed object. This operation does not require the

operator to place her hands underneath the dies or in any dangerous position and can be performed very rapidly.

Although a separate gauge is required for each different size and different contour of shoe part, yet they can be made at such a low cost that the cost of the perforating operation may be materially reduced by having a number of each particular gauge to permit the same to be loaded with shoe parts by cheap unskilled labor rather than by the expensive skilled operator of the perforating machine. In such a case, the loaded gauges may be delivered to the operator in stacks and she then merely runs them off in the perforating machine rapidly and without loss of time. This will be found to increase the speed of this work materially and to reduce the cost of this operation.

The unloading may likewise be the duty of the unskilled labor. When the gauges are used in this manner it may be found advisable to use the last form described in which the recess is closed at the back because such gauges may be subjected to vigorous handling without disturbing the position of the shoe parts therein.

It will be observed that by the use of my invention the work of perforating individual shoe parts is greatly simplified, improved in quality and alignment and materially reduced in cost. In addition, the simplification of the dies by the eradication of the outline cutting-knife eliminates a further element of cost. The rapidity, however, with which the work may be placed in position in the machine, perforated and removed therefrom is an important feature in reducing the cost of that operation.

Although my invention is illustrated as embodied in a gauge which is suitable for use in the perforating machine of the patent to be hereinbefore referred to, yet it may be applied to perforating machines of other types generally, in some cases perhaps necessitating slight changes in the gauge, all of which, however, will be apparent to one skilled in the art.

It is to be understood that my invention is not to be limited to the specific form of gauge herein shown and described since it may be embodied in other forms of construction, all within the purview of the following claims.

What I claim is:—

1. A gauge for perforating machines comprising a plate having a cut-out portion or opening for holding a shoe part by frictional engagement between the edge of said shoe part and the edge of said cut-out portion, said cut-out portion being of the same contour and size as said shoe part, and means for positioning said gauge in the machine.

2. A gauge for perforating machines com-

prising a plate having a cut-out portion or opening designed to receive and hold in flat condition the shoe part to be perforated, said opening being of a size and shape corresponding to the size and shape of said shoe part in order to hold said shoe part within said opening by frictional engagement between the edges of said opening and said shoe part.

3. A gauge for perforating machines comprising a plate having a central opening of a size and shape suitable for receiving and holding in flat condition the shoe part to be perforated, the edge of said opening being formed for frictional engagement with the edge of said shoe part to hold the same within said opening and means for positioning said plate in the perforating machine.

4. A gauge for perforating machines in plate form having an interior cut-out portion or opening for holding the shoe part to be perforated in flat condition by frictional engagement between the edge of said cut-out portion and the edge of said shoe-part and means for detachably positioning said gauge in the machine.

5. In a device of the character described, the combination with a work-support of a plate gauge having an interior cut out portion or opening for receiving in flat form and positioning the work to be operated upon, said opening being of a form corresponding in size and contour to the size and contour of the said work in flat form, and means for positioning said gauge on said work-support.

6. A gauge for perforating machines in plate form having a centrally located cut-out portion of a shape and size to receive and hold the shoe part, the edge of said cut-out portion being roughened to give a frictional contact with the edge of the shoe part to hold it in said opening.

7. A perforating machine having, in combination, a work-support, a gauge-support mounted on said work-support and provided with positioning pins and a plate having an opening for receiving and holding the shoe part to be perforated, said opening corresponding in size and shape to said shoe part to permit it to be mounted in said opening and held therein by frictional engagement between the edge of said shoe part and the edge of said opening; said plate being provided with holes to receive the positioning pins on said gauge-support in order to position said plate thereon.

8. The combination in a perforating machine of a plate having a cut-out portion of a shape and size to receive and hold a shoe part by frictional engagement between the edge of said shoe part and the edge of said cut-out portion, the plane of said shoe part being substantially in alignment with the

plane of said holder and means for removably positioning said plate accurately in said perforating machine.

9. In a perforating machine, the combination with a work-support provided with positioning pins of a plate having a centrally located cut-out portion of a shape and size to receive and hold a shoe part in flat condition by frictional engagement between the edge of said shoe part and the edge of said cut-out portion, said plate being provided with suitable holes whereby it may be mounted on said pins and positioned accurately on said work-support.
10. A perforating machine having, in combination, with a work-support, a pin-carrying support and a plate-gauge having a cut-out portion or recess for holding a shoe part for perforating and with suitable holes to receive the pins on said pin-carrying support for positioning the gauge on said work-support.
11. A gauge for perforating machines having a cut-out portion fitting the shoe

part to be perforated, said gauge having on 25 its lower side a flange projecting inwardly into said cut-out portion supporting the edge of said shoe part in said cut-out portion.

12. A gauge for perforating machines 30 comprising a plate having a cut-out portion for holding the shoe part to be perforated, said cut-out portion being covered on the lower side of said plate by a thin paper layer for supporting said shoe part in said 35 cut-out portion.

13. A gauge for perforating machines comprising a plate having a cut-out portion for holding the shoe part to be perforated, said cut-out portion being covered on the 40 lower side of said plate by a thin paper layer for supporting said shoe part in said cut-out portion and means for positioning said plate in the machine.

In witness whereof, I hereunto set my 45 hand this twelfth day of January, 1924.

WILLIAM F. LAUTENSCHLAGER.
